UNITED STATES PATENT OFFICE.

SAMUEL CLELAND DAVIDSON, OF BELFAST, IRELAND.

CENTRIFUGAL FAN AND PUMP.

1,149,638.

Specification of Letters Patent. Patented Aug. 10, 1915.

Application filed September 25, 1912. Serial No. 722,220.

To all whom it may concern:

Be it known that I, SAMUEL CLELAND DAVIDSON, of Sirocco Engineering Works, Belfast, Ireland, have invented certain new and useful Improvements in or Relating to Centrifugal Fans and Pumps, of which the following is a specification.

My invention has reference to centrifugal fans and pumps (which are hereinafter included in the term "fans") wherein the fluid dealt with (whether gaseous or liquid, both of which are included in the term "air") enters axially and is discharged circumferentially.

My invention is applicable to fans furnished with a fan wheel of the drum type, such as described in my prior Patent No. 662395, but the phenomena to which I proceed to call attention exist in other types of fans and so far as this is the case the principle of my invention is applicable to such other fans.

Referring to the drawings:—Figures 1 and 2 are vertical sections respectively of a single and a double inlet fan of known construction, the casings being omitted; Fig. 3 is a similar view of a single inlet fan, the front casing wall being shown; Figs. 4, 5, 6, 7, 8 and 9 are views similar to Figs. 1 and 2, illustrating various embodiments of the present invention; Figs. 10 and 11 are plan views showing the arrangement of the guide blades; Fig. 12, is a sectional view showing a modified arrangement of the guide blades;

Figs. 13 and 14 are sectional views showing the present invention as applied to wall fans; Figs. 15 and 16 are respectively vertical section and side elevation of the invention as applied to an incased fan; Fig. 17 is a sec-

tional elevation of a modified construction of incased fan; Figs. 18, 19 and 20 are respectively vertical section, side elevation and plan of a modified construction of single inlet wall fan; Fig. 21 is a view similar to Fig.

18 showing a double inlet fan; Figs. 22 and 23 are modifications of a conical fan shown in vertical section; Fig. 24 is a vertical elevation; chiefly in section, of a wall fan embodying the invention and applied to a ventila-

tor; Figs. 25 and 26 show in sectional elevation and side view respectively a modification of the construction shown in Fig. 11; Figs. 27 and 28 are respectively sectional elevation and side view of an incased fan employing guide vanes; Fig. 29 is a sectional

view of the improved fan arranged to work in series.

When a fan wheel which takes in air axially and discharges it circumferentially is rotating, the fluid discharged from the circumference of the fan wheel is not thrown off the tips of the blades in an even manner along their entire axial length. If for example, a fan wheel which is open to the air at one end only, as indicated in Fig. 1, be rotated in the open without an inclosing casing of any sort, the outward discharge of air is always strongest from the end of the fan wheel which is completely closed (hereinafter called the back end) as indicated by arrows *a a*. The strength of this centrifugal discharge gradually diminishes and becomes practically *nil* at a point *O* about midway therefrom toward the intake end of the blades, and from this point the current through the blades gradually assumes a centripetal flow, which is strongest at the extreme intake end, as shown by arrow *b*. The current discharged from the back portion of the blades has a tendency to and a portion of it actually does curve over toward the intake end, and re-enters the interior of the fan wheel partially centripetally from *O* to *b*, and partially around the intake ends of the blades as indicated by arrows *b' b'* and *c' c'*. At the same time, there is also the usual axial inflow of air as indicated by arrow *c* into the interior of the fan wheel (hereinafter called the intake chamber).

In the case of a fan wheel of the double intake type, as shown in Fig. 2, where the fluid enters at both of the opposite intake ends thereof, and whether the blades employed therein are mounted on each side of a disk, midway between the two opposite intake ends, or carried by centrally located spokes or arms, suitably mounted or keyed on to the driving shaft, then that half, or thereabout, of the total axial length of the blades which is midway between, and equally distant from, both intake ends of the fan wheel, discharges the fluid centrifugally outward, as indicated by the arrows *a a* and an inward centripetal flow exists, as indicated by arrows *b* and *b'* at the two opposite intake ends of the blades in the same manner as already described in respect of the single intake fan wheel shown in Fig. 1, and there will be two neutral points *O O* each at about one-quarter of the total axial

length of the blades from each of the intake ends. When the fan wheel is rotated within a casing of the usual form, with a plate L forming one side of the casing with an eye as indicated in Fig. 3, the stream lines of the air flow much the same. To find the direction of the stream line in any case at any particular point I have generally used streamers of thread or other suitable material attached to the end of a wire (hereinafter referred to as "current indicators"). My investigations have shown that these phenomena take place with very different forms and constructions of centrifugal fan wheels in which air enters axially and is discharged circumferentially, and with many different forms and arrangements of the blades therein. In particular I have found that the length or shortness of the blades in an axial direction and the sloping of the external or internal edge of the blade to the axis or having the blades arranged obliquely to the axis or of a hyperboloid formation do not within wide limits substantially alter or affect the above phenomena, there being still in most cases a centripetal flow acting through the part of the blades which is nearest the intake end of the fan wheel (hereinafter for conciseness of description referred to as the "negative" part or end of the blade or of the fan wheel) combined with the centrifugal discharge from the part thereof farthest from the said intake end (hereinafter referred to as the "positive" part or end of the blade or of the fan wheel). I have found that the phenomena occur with fan wheels of what are ordinarily known as the paddle wheel type, having radially deep blades comparatively few in number, and also with fan wheels of the type known as multibladed, or drum construction, with radially shallow and numerous blades or with corrugated blades and also with a drum consisting of a cellular or honeycomb structure around the circumference of the wheel operating like blades. In fact my observations have shown that these phenomena only cease when the eye or inlet opening to the fan wheel is closed to a considerable extent from the circumference inward, or when the axial length of blade at the periphery is much less than the axial length at or near the hub, and the sides of the blades are shrouded, both of which constructions introduce elements which tend to check the hereinbefore described inward and outward flow through or between the blades.

My hereinafter described improvements are not limited to any special form, configuration, or arrangement of blades, or of their equivalent, or to any special form or construction of fan wheel, as long as the blades and their mounting on the fan wheel are such that when revolving the before-mentioned phenomena exist. In order to

deal with these phenomena I have made many experiments with many different types of fans extending over several years, and in the course of these experiments have applied for patents for inventions dealing in a more or less incomplete manner therewith, viz: Nos. 801,303 and 820,398. By my present invention I am enabled to utilize these phenomena in such a way as to obtain greatly improved results.

According to my present invention I so arrange the fan wheel in relation to the case or other space in which it rotates that the air which passes through the negative portion of the blades is mainly taken from the suction or intake side of the fan (instead of being to a considerable extent a recirculation back from the discharge side), and so that the air thus entering centripetally through the negative end of the blades or passing axially between or along the same is discharged centrifugally through or from the positive portion of the blades. I secure this result by means of a partitional device located relative to the periphery of the fan wheel and which substantially restricts the air passing centripetally through and axially along the negative portions of the blades to that mainly taken from the suction or intake end of the fan and which opposes the tendency of the air discharged through the positive ends of the blades to recirculate to the negative ends. This partitional device may have numerous forms: Among those illustrated are by dividing the space outside the periphery of the fan wheel by a partition located near the neutral point of the blades, or by a suitable form of eye which may be furnished with guide plates or by a combination of partition with guide blades or by locating the fan within a duct which is of such greater diameter than the fan wheel that a substantial space is left between the periphery of the fan wheel and the said duct, and said duct may be furnished with guide blades extending over the negative portion of the blades. In each case both sides of the negative portion of the blades rotate in the fluid which is entering on the suction side of the fan and has not yet passed through the positive part of the blades. Under such circumstances I am also enabled by a suitable enlargement of the eye of the fan casing or of the space or suction duct in which the fan rotates to obtain a flow of air direct from the suction side of the fan into the discharge side of the fan without such air passing through the blades at all. To assist this induced flow of air suitable guide plates are or may be placed in the eye or in the space surrounding the fan wheel.

In my improved fan the air which comes through the negative portion of the blades centripetally or axially along their outer

circumference, is drawn from the outer air and thus swells the volume entering the eye axially, instead of being taken as heretofore by recirculation from the volume of air 5 which has already passed through the positive portion of the blades. I am thus enabled to prevent to a great extent the churning of air which has heretofore taken place, when a portion of the air which has passed 10 through the positive portion of the blades is again passed through the negative portion to be again passed through the positive portion. Thus the intake of air is now not only axial but partly circumferential and 15 centripetal, and in some cases a portion of the air is taken in by induction without passing through the fan wheel.

Fig. 4 illustrates the effect of a partition or dividing plate z (which may form the 20 side of the fan casing or the wall or side of a compartment into which the discharge takes place) applied in accordance with my invention at or near the neutral point O of the blades instead of near the intake ends thereof as shown in Fig. 3. With the arrangement in Fig. 4 on applying the current indicator, it will be found that on the suction side of the plate z the already described 25 axial flow c through the intake opening of the fan wheel exists, and conjointly therewith a centripetal flow, also from the outer air on suction side of the plate z , as indicated by arrows b , through the spaces between the projecting ends of the blades. On examining the currents on the other side of 30 the dividing plate z , the current indicator shows that although the outward current is comparatively weak close to the dividing plate z , this portion of the axial length of 35 the blades is now discharging outwardly throughout its length, as indicated by arrows a .

With a double intake fan, as shown in Fig. 5, the arrangement for each half of the fan is similar to that indicated in Fig. 4. The air now enters at both intake ends of the fan wheel, the centrifugal discharge is from that portion of the axial length of the blades which is centrally located between 40 the two intake ends, and which therefore constitutes the "positive" part thereof, thus leaving the centripetally acting or "negative" portions at each end extending for about one-quarter of the axial length from 45 each of the two intake ends of the blades. On rotating the fan wheel and applying the current indicator, there will be found at each of the opposite intake ends an axial flow c into the center of the fan wheel, and the inward or centripetal flow b will be found from the outer circumference of the 50 intake ends of the blades which projects or protrudes into the suction side through the dividing plates z and the outward discharge a will be between the plates z .

A fan wheel, such as indicated in Fig. 5, may be made with a central disk, and blades projecting on each side thereof, or the blades may extend in one length from one intake end to the other, and be centrally supported by arms or spokes, or they may be mounted 70 on spokes at each end, with or without a central disk or spokes and the same phenomena exist. Thus by the use of a partition or partitions such as z according to my invention I obtain a centrifugal fan in which the contrary currents at the negative and positive portions of the fan blades have been separated and utilized so as to work 75 in unison one with the other, and in combination with the ordinary axial inflow. 80

In applying my invention to a single intake fan wheel such as is indicated in Fig. 1, I have employed a side wall of the casing as the partitional device. As shown in Fig. 4, the negative end of the fan wheel is arranged to protrude outward beyond the side of the casing for the required distance so that the side wall of the casing may fulfil the office of the before-mentioned partition z or, in the alternative, the side wall of the casing on the inlet side may be recessed inward around the intake side of the fan wheel as shown in Fig. 6, leaving the blades projecting outward from the casing for the required distance. Either way the casing acts as the before-described partition z . The negative end of the fan wheel will thus protrude outward from the casing when the casing is recessed, the recess as illustrated 90 in Fig. 6 flares outwardly so that its outward diameter is larger than the fan wheel, while its inner termination is only slightly larger but said recess may be varied in form and dimensions to suit requirements and 95 may either be freely open to the atmosphere, or may form the termination of a duct leading 100 up to the fan. 105

In the construction shown in Fig. 6, the casing is recessed around the eye, and the area for entry of air through the blades into the casing is reduced. The sectional area of the air passage through the casing should be substantially undiminished or even increased so as to provide for the same or an increased flow of air notwithstanding the diminution of the area of entry through the blades as illustrated in Fig. 6. A fan thus constructed according to my invention is 110 specially applicable for compounding in series. To prevent any undue rotation of air being established outside the circumference of the projecting negative end of the blades, when in the open or in the recess or cavity in which the negative end of the blade revolves, stationary guide blades may be fitted around the said negative end, and, if required, these guide blades may be attached to the inner circumference of the recess or 115 the exterior of the side wall of the casing. 120 125

The said guide blades may be arranged in radial planes or obliquely thereto, and may be oblique to the axis of the fan, or at some suitable deflecting angle. I find that guide blades disposed at an angle of 30° to the plane of rotation and leading in the direction of rotation give good results. In some cases another series of fixed guide blades may be employed around the fan wheel, on the positive side of the said partition to suitably engage and guide the air which is being discharged, or even to guide and divert the flow of air in a suitable direction when my invention is applied to compounding in series.

In the arrangement indicated in Fig. 7 the part of the recess toward the positive end of the fan wheel is somewhat increased in diameter as compared with the previous illustrations so that there is a considerable space between the most contracted portion and the periphery of the fan wheel. In this space is located the partitional device which consists of guide blades *g* which may be placed obliquely to the axis and have openings between.

In the arrangement indicated in Fig. 8 that portion of the casing *Y* which forms the eye is now continued toward the back end. The opening of the eye is now most contracted in the neighborhood of the neutral point and the eye *Y* may be furnished with guide blades *g*, which may be straight as in Fig. 20, although it is not essential that they should be straight, as a curved form is operative, and may be employed. The blades are preferably oblique to the axis as in Fig. 20. In the arrangement of Fig. 8 it will be seen that the casing is no longer a partition in the same sense as in Fig. 6 and the fan may be said to rotate in a duct *Y* of larger diameter than the fan, the air being drawn in at one end and discharged at the other. It may have the form of a double cone instead of a curve as shown in Fig. 8, and this double cone may be combined with a partition.

From the above illustrations it will be obvious that the principle of my invention may be applied in widely different ways, so long as it is arranged that the air which feeds the negative end of the blades comes mainly from the suction side of the fan and is not taken by recirculation back from the air which has already passed through the positive portion of the blades. It will further be observed that my invention leads to the important development in which the air drawn in axially into the fan wheel is combined with air drawn in through the negative ends of the blades and also with air drawn in around the periphery of the blades without passing through the blades at all. The result of such an arrangement is that the frictional loss due to high velocity of

flow on the suction side is greatly reduced. As a consequence of this the size of diameter of fan wheel which will deal with a given volume of air will also be considerably reduced.

It is obvious that my improvements may be applied either with or without a casing, according to the conditions pertaining to the employment and location of the fan wheel, provided that the fluid to be operated on by the negative part or parts of the fan wheel be separated from that which discharges from the positive part thereof, in accordance with the principles hereinbefore indicated. In the arrangement shown in Fig. 8 the fan wheels may be regarded as being placed in a space which forms a *vena contracta* and some of the improved results which arise from this form may be regarded as flowing from the combination of a fan wheel with an inclosed space in the form of a *vena contracta*. The cavity or recess into which the negative end of the fan projects may in some cases be eccentrically disposed or may be of spiral form, and the wall or walls thereof may be either rectangular, curved, or angled in cross section.

An important application pertaining to this invention is that fans constructed upon these principles may be arranged or compounded so as to work in series. For example, two or more fans may be so mounted relatively to one another, and within a suitable inclosing casing, that the air discharged from the positive end of the first fan wheel may enter the negative end of the second, and so on, whereby an increased pressure is obtained in the discharge from the last wheel in the series. The casing wherein said fan wheels operate may be provided with suitable partitions or fixed guide blades fulfilling the office thereof or with suitable contracted portions, with or without fixed guide blades. A suitable intermediate space or chamber with or without suitable guide blades is provided between the closed back of the first fan wheel, and the open intake end of the succeeding one, whereby the air discharged from the positive part of the first fan wheel is guided to the negative part and intake opening of the intake end of the succeeding fan wheel, and so on.

Figs. 4, 5, 6, 7 and 8 may be said to represent diagrammatically either a wall fan or an incased fan. In constructing a wall fan according to this invention the inclosing frame or the aperture in the wall will be constructed to embody the features mentioned. With an incased fan, it will be readily understood that the partition *z*, Figs. 4, 6 and 7, will form one wall of the casing, and in Fig. 5 the two plates *z z* form the two sides of a discharge passage. The casing will extend over and inclose the positive part of the fan, or the sides of the

casing may spring from that part of the eye which is of smallest diameter or where the eye joins the end of the guide blades, which projects toward the discharge end, or the 5 casing may spring from the inner end of a duct such as 'Y' Fig. 8, constructed as described, and inclosing more or less of the length of the fan blades. The casing may be of the usual snail-shaped type or that 10 part of the casing which extends over the positive part of the blades may be of cylindrical form suitably enlarged or flared outward over the positive end of the fan, and adapted to deliver the air into a delivery 15 portion of the casing disposed alongside at the back end of the fan, said delivery part of the casing being either cylindrical, snail-shaped, or other suitable shape, as may be selected. 20 The drawings accompanying this specification and numbered 9 to 29, show some further diagrams and several constructional forms of fans embodying my invention.

Figs. 9, 10, 11 and 12 are some further 25 diagrams showing modified arrangements of the guide blades. In Fig. 9, the partition Z is shown provided with guide blades g on the negative side of the wheel, and guide blades g' on the positive side. The guide 30 blades may be employed on both sides. These are preferably inclined as at Fig. 10 as shown, or those on the negative side or positive side alone may be used. Figs. 10 and 11 show in developed plan views several 35 modified arrangements of the guide blades. In Fig. 10 which may be considered to be a plan of Fig. 9, g g' are the guide blades on the negative side, and g' g the guide blades on the positive side. The long arrow indicates the direction of rotation of the fan 40 wheel. Fig. 11 shows a further modification in which a partitional device consisting of three rows of guide blades of similar angularity are employed alternated one with the other, and without any partition such as Z , although the intermediate series g^2 corresponds with the position of the said partition Z . Fig. 12 shows in diagram a further 45 modification, wherein in addition to the guide blades g outside the periphery of the wheel, guide blades g^3 are provided extending axially along within the fan blades, and these guide blades g^3 are illustrated as carried the full length of the blades but this 50 length is not essential and they may if desired be made shorter than the full length of the blades. The said guide blades g^3 may be either parallel to the axis or disposed at an angle which may correspond with that 55 of the guide blades g . If required a closed drum-like casing m may be provided within the inner edges of the guide blades g^3 and this drum may extend part way inward or it may be carried substantially the full 60 length of the blades. Further, if required, 65

the inner and outer guide blades g^3 and g may be coupled together or made in one piece at the intake end of the fan, as indicated at g^4 . The angular disposition of the guide blades g is shown in the developed 70 plan view, Fig. 30. Where the central drum m is employed the fan wheel may be said to rotate in an annular space with guide blades on the inner or outer sides, or both.

Fig. 13 is a sectional elevation showing a 75 wall fan where a fan wheel A is mounted so that its negative end rotates within an aperture 2 in a wall 3. The aperture 2 is considerably larger in diameter than the fan wheel A , so as to leave a suction space 2 80 between the sides of the aperture and the periphery of the negative end of the fan blades. The positive end of the fan wheel projects on the discharge side of the wall, and about mid-way between the ends of the 85 blades, and, on the inner face of the wall 3 is fitted a partition plate z dividing the space outside the periphery of the fan wheel, and operating in the manner hereinbefore set forth. The positive ends of the blades 90 discharge the air circumferentially outward between the partition z and a fixed shield plate 4. The said plate 4 may if required be provided by an outward extension of the back plate of the fan wheel, instead of being 95 fixed as shown.

Fig. 14 shows a double intake fan wheel fitted to discharge air into a space 5 between the two walls 3, 3. The apertures in these 100 walls may form the termination of two ducts or airways from a mine or building. This construction need not be further described as the parts are a duplication of those shown in Fig. 13, with the exception that the plate 4 of said figure is omitted, both the positive portions a a of the double 105 fan wheel A discharging into the space 5 between the walls 3.

Figs. 15 and 16 show in cross-section and 110 side elevation respectively a cased fan where the negative end b of the fan wheel is mounted so as to rotate in a suction duct or eye 6 of considerably larger diameter than the periphery of the fan wheel, a partition Z being fitted in a similar manner to Fig. 13. In this cased fan construction the air which 115 is discharged from the positive end a of the fan wheel blades is discharged directly into the spiral volute of the casing 7, which casing is extended as shown axially beyond the back of the fan to provide the necessary area for the volume of air which is being discharged, the central part of the casing may be occupied by a recessed chamber 8.

Fig. 17 shows in sectional elevation one 120 form of the cased fan made in accordance with my invention. In this construction the spiral or volute casing 7 is of ample dimensions for receiving and discharging the volume of air discharged from the positive

end of the fan blades and has a fan wheel mounted therein in the usual manner. The suction duct or eye 6 is carried inward over the fan wheel to about the neutral point *a* of the blades whereby the negative part *b* of the blade is entirely inclosed in or projects into the said eye or duct 6 which is flared outwardly or made of conical form as shown so as to admit the air centripetally through the negative part *b* of the blade. *g* are guide blades fitted on the interior of the eye 6, the inner edge of these blades being suitably spaced away from the periphery of the fan wheel. The positive or discharging end *a* of the blades discharges into the casing 7 from which the air is delivered in the usual manner. It will be seen in this construction that the wall of the eye 6 serves as a partitioned device to divide the space outside the fan wheel so that the discharge from the positive portion *a* of the fan wheel is prevented from returning to the negative part *b* in the manner and for the purposes hereinbefore set forth.

Figs. 18, 19 and 20 show a modified construction of single intake wall fan applied as a mine fan, and where guide blades *g* are employed, and Fig. 21 is a sectional elevation showing a similar construction applied to a double intake mine fan. In these constructions as shown the partition *Z* is dispensed with, and the suction eye or duct 2 (Figs. 18 and 19) or ducts 2, 2 (Fig. 21) are fitted on their inner circumference with guide blades *g* which operate in the manner before described; the said guide blades are disposed obliquely to the axis of the fan wheel as shown in Fig. 20, which shows a portion of the suction eye developed. The duct 2, or ducts 2, 2, where they extend over the fan on the discharge or positive end may be flared outwardly as at 9, the guide blades being shaped to correspond. With these constructions, a portion of the air dealt with enters the fan not only axially and centripetally, but also passes in between the guide blades from the suction to the discharge side of the fan wheel without passing through the fan blades, as before described, and is discharged into the space 10 together with the air which has passed through the fan blades.

Fig. 22 shows a modified construction in which a conical form of fan is employed mounted in a conical aperture or duct which is sloped to conform with the conicity of the fan wheel. The walls of the aperture or duct may be parallel with the fan axis as in Fig. 23 instead of conical. The guide blades *g* are oblique to the axis of the fan wheel in Figs. 22, 23 and 24.

Fig. 23 shows a further modification wherein the fan wheel has the positive part *a* parallel to the axis and the negative part *b*

of conical shape. This construction may be modified to the extent that both the negative and the positive portions may be sloped at different angles, that is to say, while the negative portion can be conical the positive half need not be parallel to the axis but may be more or less sloped at a different angle to that of the negative portion. The fan wheel is shown as having the negative portion rotating in an aperture, the walls of which are parallel to the fan axis, but the said walls may be made parallel to the negative portion of the fan wheel as in Fig. 22.

Fig. 24 shows a wall type of fan applied to the ventilator of a ship's stokehold, the fan wheel *A* being mounted directly on the shaft of a steam turbine, or other high speed prime mover, 10, and disposed at the lower end of a ventilator 11. The construction is similar to Fig. 13, and the fan discharges the air all around in a horizontal direction over the ceiling of the room or hold 12.

Figs. 25 and 26 show in sectional elevation and side view a modified construction of Fig. 11, wherein guide blades *k* are disposed around the discharge from the positive ends of the blades. The said guide blades *k* may be flat as shown in Fig. 25 in hard lines, or they may be curved, and they may be disposed tangentially, or at other suitable angle so as to promote the outward discharge of the air from the circumference of the fan. 4 is the annular shield plate already described with reference to Fig. 13.

Figs. 27 and 28 are respectively sectional elevation and side views of a cased fan where guide blades *g* and *g'* are substituted as partitional devices for the partition *Z*. In this construction that portion of the duct 2, in which the guide blades *g'* are mounted covers the positive end of the fan blades, and is flared outwardly to deliver the air into one side of a spiral casing 7, which is entirely beyond the back end of the fan, and has a central recessed chamber 8 of the same diameter as the fan wheel or substantially so, and the dotted line 13 in Fig. 28 shows the outer circumference of the annular discharge from the fan wheel within the spiral casing. The guide blades *g*, *g'* are oblique to the axis substantially as in Fig. 20. The casings illustrated are only examples, and may be modified to suit requirements.

Fig. 29 shows in diagram one arrangement of the improved fan compounded or arranged to work in series. *A* *A'* are the fan wheels spaced apart so as to provide an annular space *p* between them. The first fan *A* of the series is shown with guide blades *g*, arranged oblique to the axis as in the construction hereinbefore described, and without a partition *Z* (which may however be employed if desired) while the second fan wheel *A'* is provided with the partition *Z* as in the construction hereinbefore de-

scribed. The guide blades g of the second fan A' are also obliquely arranged and are extended over the negative end of the fan blades and beyond the same toward fan A , 5 and project inward at g^5 so as to direct a portion of the air discharged from the fan A , from the circumference of the casing toward the center of the space p , while the remainder of the air passes along the guide 10 blades g toward the partition Z , and thence centripetally through the negative ends of the fan blades A' . A fixed disk-like plate, p' is mounted at the back of the first fan wheel A and supported from the casing spokes and 15 a drum p^3 may be fixed thereon so as to be supported thereby and is carried forward into the intake chamber of the fan wheel A' . The drum p^3 is shown as extending right up to the back plate of the fan wheel 20 but this is not essential and it may extend for only half the length shown or part way. Guide blades such as g^6 may be mounted at any suitable angle on the outer surface of the drum p^3 but are preferably parallel with 25 the axis. This construction is only to be taken as an example, and it is to be understood that the arrangement of the compound fan may be varied as required, as long as one or all of the fans employed embody the features of the present invention. 30

Instead of the hereinbefore described devices as represented in Fig. 29 by g^5 g^6 , p' and p^3 , for guiding the air discharge from the first fan into the second I may employ 35 separate intermediate stationary guide blades projecting from the casing into and partially or substantially occupying axially the space between the back of the first or preceding fans of the series, and the negative end of the second or succeeding fan, and 40 in their axial direction these blades may be flat or curved with the concave of the curve facing the direction of the air discharge from the first fan, while in their radial direction they may be either curved or straight 45 and set radially or at any suitable angle relative to a radial line and may be shaped so as to project into the interior of the second or succeeding fan wheel. With the 50 compound fan the discharge areas from the second and succeeding fans should be so reduced in area as to allow only the discharge of sufficiently reduced volume to prevent the second or succeeding fan setting up 55 a suction on the discharge of the preceding or first fan and the blades of the second or succeeding fan wheel may have their axial length shortened relatively to that of the first or preceding fan wheel in suitable proportion to the increased pressure set up by 60 each succeeding wheel.

For convenience of illustration, the drawings herein described show a fan wheel of the type described in my prior Patent No. 662395, but it is to be understood that other

types of fan wheel, such as hereinbefore referred to, may be substituted as preferred.

In the foregoing description of my invention and in the accompanying drawings, I have described and illustrated several 70 equivalent constructions embodying my invention, *i. e.*, a partition in its several forms shown, guide blades in the several constructions illustrated and the restricted aperture (as in Fig. 8), and by use of the term "partitional device" in the claims, I mean to include all these forms in which my invention may be embodied, and other equivalent forms which may be substituted. It will therefore be seen that my invention is not 80 limited to the constructions illustrated, although I have endeavored to illustrate the best mode of constructing the same known to me, but that other and equivalent devices may be employed within the limits of the 85 appended claims.

What I claim as my invention and desire to secure by Letters Patent is:—

1. In a centrifugal fan or pump, a fan wheel provided with blades, and a partitional 90 device located relatively to the periphery of the fan wheel to substantially restrict the fluid which passes through centripetally or axially along the negative portion of the blades to that which is mainly taken from the 95 suction or intake side of the fan.

2. In a centrifugal fan or pump, a fan wheel provided with blades, the negative ends of the blades protruding into and exposed to the space from which the air is 100 drawn into the fan so that the air enters the fan wheel from said space both centripetally and axially and the positive parts or ends of the blades being exposed to the space into which said air is circumferentially discharged, combined with means near said last named space to prevent the discharged air from returning to the space from which the air is drawn. 105

3. In a centrifugal fan or pump the combination of means which divide the space from which air is drawn from the space into which the air is discharged, a fan wheel so mounted in relation to said means that the negative ends of the blades protrude into 110 and are so exposed to the space from which the air is drawn into the fan that the air enters the fan wheel from said space both centripetally and axially while the positive ends of the blades are exposed to the space 115 into which said air is circumferentially discharged, said fan wheel and said dividing means being mounted in such relation that sufficient space is left around the periphery of the fan wheel for a portion of the air to pass by induction along the outside of the periphery from the suction to the discharge. 120

4. In a centrifugal fan or pump a fan wheel adapted to take in air axially and to discharge the same peripherally in combina- 125 130

tion with means whereby the space around the periphery of the fan wheel is divided consisting of a partition located near the neutral part of the blades.

5 5. A centrifugal fan or pump adapted to discharge the air peripherally in combination with a partitional device located relatively to the periphery of the fan wheel for separating the space from which the air is 10 drawn and the space into which it is discharged, an open duct comprising said partitional device and extending parallel to the axis of the fan, said duct being of substantially larger diameter than the fan wheel 15 and extending over the same from the suction to the discharge.

6. A centrifugal fan or pump comprising a fan wheel in combination with a duct of larger diameter than the fan wheel, said fan 20 wheel being adapted to rotate in said duct and said duct being so shaped as to be of minimum diameter at or near the neutral part of the blades and whereby the air dealt with enters the one end of said duct and is 25 discharged at the other.

7. In a centrifugal fan or pump, the combination of a fan wheel, means for separating the space from which the air is drawn from the space into which it is discharged, 30 comprising fixed guide blades located outside the periphery of the fan wheel so that a portion of the air dealt with passes between said guide blades to the discharge side of the fan wheel as well as into and 35 through the fan wheel.

8. In a centrifugal fan or pump, the combination of a fan wheel, means for separating the space from which the air is drawn from the space into which it is discharged, 40 comprising fixed guide blades angularly disposed and located outside the periphery of the fan wheel so that a portion of the air dealt with passes between said guide blades to the discharge side of the fan wheel as 45 well as into and through the fan wheel.

9. In a centrifugal fan or pump, the combination of a fan wheel provided with blades, means for separating the space from which the air is drawn from the space into 50 which it is discharged, and fixed guide blades, tangentially disposed, and fitted around the periphery of the fan wheel outside the positive ends of the blades.

10. In a centrifugal fan or pump, the combination with a fan wheel provided with 55 blades, of means for admitting air to the said wheel both centripetally and axially, and means for separating the space from which the air is drawn from the space into 60 which it is discharged, comprising fixed guide blades angularly disposed around the periphery of the fan wheel outside the positive ends of the fan wheel blades.

11. In a centrifugal fan or pump, the

combination with a fan wheel provided with 65 blades, of a duct leading from the space from which air is drawn to the space into which air is discharged, a fan wheel adapted to rotate in said duct, said duct being of larger diameter than the fan wheel and having 70 guide blades fitted on the inside and disposed obliquely relative to the axis, the said duct, the guide blades thereon, and that portion of the fan wheel which is concentrical with said duct all being of conical 75 shape.

12. In a centrifugal fan or pump, a fan wheel having a portion of conical shape combined with a duct, fitted on its inside 80 with guide blades which have their inner edges sloped or shaped to follow the conicity of the fan wheel, and are obliquely disposed relative to the axis.

13. In a centrifugal fan or pump a casing into and through which the fan discharges, 85 a fan wheel provided with blades and mounted in said casing, the negative end of said wheel protruding into the space from which the air is drawn and exposed both peripherally and axially to said space so 90 that the air from said space enters the fan wheel both axially and centripetally, the positive ends of said blades projecting into and discharging peripherally into said casing.

14. In a centrifugal fan or pump the combination with a fan wheel provided with blades, of means for separating the space from which the air is drawn from the space into which the air is discharged, the negative ends of said fan wheel blades being exposed to the space from which the air is drawn in such manner that the fan wheel is adapted to take in air both axially and centripetally, a casing inclosing the space 100 into which the positive ends of the blades discharge, the positive ends of said blades delivering air peripherally to said casing and said casing being adapted to collect and deliver the air in the required direction. 110

15. A centrifugal fan or pump comprising a fan wheel provided with blades and means for separating the space from which the air is drawn from the space into which the air is discharged the negative portion of 115 the fan wheel being exposed to or protruding into the space from which the air is drawn so that the fan wheel takes in air both centripetally and axially, a casing inclosing the space into which the positive 120 ends of the blades discharge, said casing comprising a part concentric with the discharge end of the fan wheel and a spiral portion of the casing into which said concentric portion is adapted to discharge.

16. In a centrifugal fan or pump the combination with a fan wheel provided with blades, of means for separating the space

- from which the air is drawn from the space into which the air is discharged, said separating means being so located in relation to said fan wheel that the negative ends of 5 the fan wheel blades are exposed to the space from which the air is drawn in such manner that the fan wheel takes in air both axially and centripetally and discharges the same circumferentially from the positive end 10 of the blades, and fixed guide blades disposed within the inner radius of the fan wheel blades.
17. In a centrifugal fan or pump the combination with a fan wheel provided with 15 blades, of means for separating the space from which the air is drawn from the space into which the air is discharged, said separating means being so located in relation to said fan wheel that the negative ends of 20 the fan wheel blades are exposed to the space from which the air is drawn in such manner that the fan wheel takes in air both axially and centripetally and discharges the same circumferentially from the positive end 25 of the blades, fixed guide blades disposed within the inner radius of the fan wheel and fixed guide blades preferably disposed at a suitable angle and fitted outside the periphery of the fan wheel blades.
18. In a centrifugal fan or pump the combination with a fan wheel provided with 30 blades, of means for separating the space from which the air is drawn from the space into which the air is discharged, said separating means being so located in relation to said fan wheel that the negative ends of the fan wheel blades are exposed to the space from which the air is drawn in such manner that the fan wheel takes in air both 35 axially and centripetally and discharges the same circumferentially from the positive end of the blades, fixed guide blades disposed within the inner radius of the fan wheel, a closed drum-like casing of much less diameter than the inner circumference of the 40 blades and disposed within the intake chamber of the fan wheel.
19. In a centrifugal fan or pump the combination with a fan wheel provided with 45 blades, of means for separating the space from which the air is drawn from the space into which the air is discharged, said separating means being so located in relation to said fan wheel that the negative ends of the 50 fan wheel blades are exposed to the space from which the air is drawn in such manner that the fan wheel takes in air both axially and centripetally and discharges the same circumferentially from the positive 55 ends of the blades, fixed guide blades disposed within the inner radius of the fan wheel and fixed guide blades preferably disposed at a suitable angle and fitted outside the periphery of the fan wheel blades, a 60 closed drum-like casing of much less diameter than the inner circumference of the blades and disposed within the intake chamber of the fan wheel.
20. In a centrifugal fan or pump, a fan wheel having axially extending blades adapted to rotate in an annular path, inclosed by an open-ended annular duct, a substantial space being provided between the inner walls of said duct, and the outer edges of 65 said blades, fixed guide blades attached to the inner faces of said duct and disposed outside of the outer circumference of the annular path of said fan blades with a clearance space between said fixed guide blades and the fan blades, and a drum with- 70 in said fan wheel and located in the intake chamber.
21. In a centrifugal fan or pump, a plurality of fan wheels compounded in series, an inlet eye to the first fan of the series of 75 substantially larger diameter than the fan wheel whereby the negative end of said first fan wheel is exposed both peripherally and axially to the said eye and is adapted to take in air both axially and centripetally, an intermediate chamber into which the positive end of the first fan wheel discharges, the second fan wheel having its negative end 80 rotating in an eye or duct of larger diameter than the periphery of the fan wheel and 85 whereby the said negative end of the fan wheel is exposed both axially and peripherally to said eye or duct and the intermediate chamber, a discharge duct or casing into 90 which the positive end of the final fan of the series discharges and means whereby the air discharged from the positive end of any 95 one fan is prevented from returning to the negative end of the same fan.
22. In a centrifugal fan or pump, a plurality of fan wheels compounded in series, an inlet eye to the first fan of the series of 100 substantially larger diameter than the fan wheel whereby the negative end of said first fan wheel is exposed both peripherally and axially to the said eye and is adapted to take in air both axially and centripetally, an intermediate chamber into which the positive end of the first fan wheel discharges, the second fan wheel having its negative end 105 rotating in an eye or duct of larger diameter than the periphery of the fan wheel and whereby the said negative end of the fan wheel is exposed both axially and peripherally to said eye or duct and the intermediate chamber, a discharge duct or casing into 110 which the positive end of the final fan of the series discharges and means whereby the air discharged from the positive end of any one fan is prevented from returning to the negative end of the same fan, means whereby air 115 may pass from the negative end of any one fan wheel through the positive end thereof.

by induction without passing through the fan wheel blades.

23. In a centrifugal fan or pump, a plurality of fan wheels compounded in series, 5 an inlet eye to the first fan of the series of substantially larger diameter than the fan wheel whereby the negative end of said first fan wheel is exposed both peripherally and axially to the said eye and is adapted to 10 take in air both axially and centripetally, an intermediate chamber into which the positive end of the first fan wheel discharges, the second fan wheel having its negative end rotating in an eye or duct of larger diameter 15 than the periphery of the fan wheel and whereby the said negative end of the fan wheel is exposed both axially and peripherally to said eye or duct and the intermediate chamber, and a discharge duct or casing 20 into which the positive end of the final fan of the series discharges and means whereby the air discharged from the positive end of any one fan is prevented from returning to the negative end of the same fan, a fixed 25 drum disposed within the inner edges of the fan wheel blades of the second or succeeding fan, and guide blades disposed upon the periphery of said drum within the inner edges of the fan wheel blades.
- 30 24. The combination of two or more centrifugal fans, each having a wheel provided with axially extending blades and adapted to discharge air peripherally, a casing inclosing said fans and providing a substantial space between the wheel and the wall 35 of the casing, and forming a compound fan wherein the air discharged from one fan is delivered to the succeeding fan, and means for preventing any material amount of air 40 discharged through the positive end of said blades from re-circulating through the negative end thereof, whereby a greater pressure of air is obtained from the last of the series than the first.
- 45 25. In a centrifugal fan or pump, the combination with a fan wheel having blades and adapted to take in air axially of means disposed around the periphery of the fan wheel and adapted to isolate the air dis- 50 charged from the positive end of the blades the negative end of the wheel being exposed both peripherally and axially to the space from which air is drawn into the fan where- 55 by the said fan takes in air both axially and centripetally and induces air to pass outside the periphery of the fan wheel from the suction to the discharge without passing through the fan wheel blades.
- 60 26. In a centrifugal fan or pump, a fan 65 wheel adapted to take in air axially and to discharge the same peripherally, in combination with means whereby the space around the periphery of the fan wheel is divided consisting of a partition located near the neutral part of the blades, the aper-

ture in said partition being considerably larger than the fan wheel.

27. In a centrifugal fan or pump the combination with a fan wheel provided with blades, of means for separating the space 70 from which the air is drawn from the space into which the air is discharged, the negative ends of said fan wheel blades being exposed to the space from which the air is drawn in such manner that the fan wheel is 75 adapted to take in air both axially and centripetally, and by induction outside the periphery of the fan wheel, a casing inclosing the space into which the positive ends of the blades discharge, the positive ends of said 80 blades delivering air peripherally to said casing and said casing being adapted to collect and deliver the air in the required direction.

28. In a centrifugal fan or pump, a fan 85 wheel having axially extending blades adapted to rotate in an annular path, and inclosed by an open-ended annular duct, a substantial space being provided between the inner walls of said duct, and the outer 90 edges of said blades, and having fixed guide blades attached to the inner faces of said duct and disposed outside the outer circumference of the annular path of said fan blades with a clearance space between said fixed guide blades and the fan blades, said guide blades so disposed relatively to the axis as to substantially prevent the re-circulation of air discharged through the positive ends of said blades. 95

29. In a centrifugal fan or pump, a fan wheel having axially extending blades adapted to rotate in an annular path, and inclosed by an open ended annular duct, a substantial space being provided between the inner walls of said duct, and the outer 105 edges of said blades, and having fixed radial guide blades attached to the inner faces of said duct and disposed outside and inside the outer and inner circumference of the annular path of said fan blades with a clearance space between said fixed guide blades and the fan blades. 110

30. In a centrifugal fan or pump, a plurality of fan wheels compounded in series, an inlet eye to the first fan of the series of substantially larger diameter than the fan wheel whereby the negative end of said first fan wheel is exposed both peripherally and axially to the said eye and is adapted to take in air both axially and centripetally, an intermediate chamber into which the positive end of the first fan wheel discharges, the second fan wheel having its negative end rotating in an eye or duct of larger diameter 115 than the periphery of the fan wheel and whereby the said negative end of the fan wheel is disposed both axially and peripherally to said eye or duct and the intermediate chamber, and a discharge duct or casing 120

125 130

into which the positive end of the final fan of the series discharges and means whereby the air discharged from the positive end of any one fan is prevented from returning to the negative end of the same fan, a fixed drum disposed within the inner edges of the fan wheel blades of the second or succeeding fan.

31. In a centrifugal fan or pump, the combination with a fan wheel having blades and adapted to take in air axially of means disposed around the periphery of the fan wheel and adapted to isolate the air discharged from the positive end of the blades, the negative end of the wheel being exposed both peripherally and axially to the space from which air is drawn into the fan whereby the said fan takes in air both axially and centripetally.

32. In a centrifugal fan or pump, a fan wheel, and a partitional device located relative to the periphery of the fan wheel, for opposing the passage of air discharged at the positive part of the blades to the negative part of said blades.

33. In a centrifugal fan or pump, a fan wheel, and a partitional device located relative to the periphery of the fan wheel, for obstructing the circulation of air discharged at the positive part of the blades to the negative part of the blades.

34. In a centrifugal fan or pump, a fan wheel having axially extending blades adapted to rotate in an annular path inclosed by an open-ended annular duct, a substantial space being provided between the inner wall of said duct and the outer edges of said blades, fixed guide blades attached to the inner faces of said duct, and a clearance space being provided between said fan blades and said guide blades, said guide blades so disposed relative to the axis as to substantially prevent the re-circulation of air discharged through the positive ends of said blades.

35. In a centrifugal fan or pump, a fan wheel having axially extending blades adapted to rotate in an annular path inclosed by an open-ended annular duct, a substantial space being provided between the inner wall of said duct and the outer edges of said blades, fixed guide blades attached to the inner faces of said duct, and inclined relative to the axis, and a clearance space being provided between said fan blades and said guide blades.

36. In a centrifugal fan or pump, a plurality of fan wheels compounded in series, each of said wheels having axially extending blades adapted to rotate in an annular path inclosed by an open-ended annular duct, a substantial space being provided between the inner wall of said duct and the outer edges of said blades, fixed guide blades attached to the inner faces of said duct and inclined

relative to the axis, a partition having a diameter substantially equal to the first fan wheel between said wheels, and a clearance space being provided between said fan blades and said guide blades.

37. In a centrifugal fan or pump, a plurality of fan wheels compounded in series, each of said wheels having axially extending blades adapted to rotate in an annular path inclosed by an open-ended annular duct, a substantial space being provided between the inner wall of said duct and the outer edges of said blades, fixed guide blades attached to the inner faces of said duct and inclined relative to the axis, a partition having a diameter substantially equal to the first fan wheel between said wheels, and a drum extending within the second wheel, and a clearance space being provided between said fan blades and said guide blades.

38. In a centrifugal fan or pump, the combination with a fan wheel provided with blades of means for separating the space from which the air is drawn from the space into which the air is discharged, said separating means being so located in relation to said fan wheel that the negative ends of the fan wheel blades are exposed to the space from which the air is drawn in such manner that the fan wheel takes in air both axially and centripetally and discharges the same circumferentially from the positive ends of the blades, and fixed guide blades disposed within the inner radius of the fan wheel blades, and substantially parallel to the fan wheel axis.

39. In a centrifugal fan or pump, the combination with a fan wheel provided with blades of means for separating the space from which the air is drawn from the space into which the air is discharged, said separating means being so located in relation to said fan wheel that the negative ends of the fan wheel blades are exposed to the space from which the air is drawn in such manner that the fan wheel takes in air both axially and centripetally and discharges the same circumferentially from the positive ends of the blades, and fixed guide blades disposed within the inner radius of the fan wheel blades, and substantially parallel to the fan wheel axis, and extending to about midway of the axial length of the blades.

40. In a centrifugal fan or pump, the combination with a fan wheel provided with blades of means for separating the space from which the air is drawn from the space into which the air is discharged, said separating means being so located in relation to said fan wheel that the negative ends of the fan wheel blades are exposed to the space from which the air is drawn in such manner that the fan wheel takes in air both axially and centripetally and discharges the same

circumferentially from the positive ends of the blades, fixed guide blades disposed within the inner radius of the fan wheel blades and substantially parallel to the fan wheel 5 axis and extending to about midway of the axial length of the blades, and fixed guide blades preferably disposed at a suitable angle and fitted outside the periphery of the fan wheel blades.

10 41. In a centrifugal fan or pump, a fan wheel having blades, and a partitional device located relative to the periphery of the fan wheel for opposing the recirculation of fluid discharged through the positive ends 15 of said blades to the negative ends thereof.

42. A centrifugal fan or pump having a multi-bladed rotor, the negative ends of the blades being exposed to the space from which the air is drawn and a partitional device 20 located relative to the periphery of the fan wheel for opposing the re-circulation of fluid discharged through the positive ends of said blades to the negative ends thereof.

43. In a centrifugal fan or pump, a fan 25 wheel having blades, a partitional device located relative to the periphery of the fan wheel and adapted to substantially guide and direct the air current which passes centripetally through or axially along the negative ends of the blades in such manner that 30 said air current is mainly taken from the suction or intake side of the fan.

44. In a centrifugal fan or pump, a casing 35 into and through which the fan discharges, a fan wheel provided with blades and mounted in said casing, the casing extending

over and inclosing the positive parts of the blades and having portions terminating near the neutral parts of the blades, the negative end of said wheel protruding into the space from which the air is drawn and exposed both peripherally and axially to said space, and said negative end adapted to draw air into the fan wheel both axially and centripetally, the positive ends of said blades 40 discharging peripherally into said casing. 45

45. In a centrifugal fan or pump, a casing into and through which the fan discharges, a fan wheel provided with blades and mounted in said casing, the casing extending over and inclosing the positive parts of the blades and having a portion terminating near the neutral parts of the blades and spaced apart from the periphery of the wheel, whereby a space is provided for the 50 passage of air into the casing without passing through the wheel, the negative ends of said blades protruding into the space from which the air is drawn and exposed both peripherally and axially to said space, and said negative end adapted to draw air into the fan wheel both axially and centripetally, the positive ends of said blades discharging 55 peripherally into said casing. 60

In witness whereof, I have hereunto 65 signed my name in the presence of two subscribing witnesses.

SAMUEL CLELAND DAVIDSON.
